Patrick O'Farrell.

UNITED STATES PATENT OFFICE.

RILEY HALSEY SARGENT, OF WALWORTH, NEBRASKA.

WIND-WHEEL ATTACHMENT.

SPECIFICATION forming part of Letters Patent No. 427,483, dated May 6, 1890.

Application filed May 6, 1889. Serial No. 309,777. (No model.)

To all whom it may concern:

Be it known that I, RILEY HALSEY SARGENT, a citizen of the United States of America, residing at Walworth, in the county of Custer 5 and State of Nebraska, have invented certain new and useful Improvements in Wind-Wheel Attachments, of which the following is a specification, reference being had therein to the accompanying drawings.

10 This invention pertains to certain new and useful improvements in wind-wheel attachments, having reference more especially to a grinding-mill operated by the power derived from the former.

15 The object of the invention is to provide means for automatically stopping the working of the wind-wheel when nearly all the grain in the hopper has been ground; and it consists of a weighted wing or plate connected 20 with a trigger or trip holding the disengaging and connecting rod of a windmill, the raising of said wing or plate causing said rod to throw the wind-wheel out of gear, substantially as hereinafter fully set forth.

25 In the accompanying drawings, Figure 1 is a front elevation showing my invention connected to a wind-wheel tower. Fig. 2 is a detail view of the hopper and its valve. Fig. 3 is a view of a modification.

30 Referring to the drawings, A designates the hopper, leading to a grinding-mill and having a lower opening a.

B is a wing or plate provided with a short arm b, projecting through a slot or opening b' in the hopper, wherein it is pivoted by a pin b². To the outer end of this arm b is secured a weight C, to which is connected one end of a rope or chain D, which is connected at its end to a right-angular trip-lever d', fulcrumed 40 on a bracket d² of a wind-wheel tower E.

F is a quadrant or lever fulcrumed to the tower E. To one end thereof is connected the lower end of a rod f, leading to the wind-wheel mechanism, and with its other end the trip-lever d' is designed to engage.

A rope or chain G is connected to the upper end of the quadrant or lever F, and after being passed over a pulley g said rope has connected thereto a weight g'.

50 In practice the grain in the hopper holds the wing or plate B down against the side thereof, and the trip-lever d' and quadrant or lever F are brought into engagement, which

will throw the wind-wheel into gear through the rod f. The power derived from the wind-wheel will effect the grinding of the grain by means not shown, whereby when the supply of grain in the hopper is nearly exhausted, as shown in Fig. 2, the wing or plate B flies into a horizontal position, causing the lowering of the weight, which will pull on rope or chain D and effect the tripping of the lever d' and quadrant or lever F. The movement of this quadrant or lever under the action of the weighted rope will pull down on rod f and throw the wind-wheel out of gear, thereby immediately discontinuing the grinding operation.

In Fig. 3 I have shown a modification of my invention, which consists in employing a bell-crank lever H and connecting the same to a lever h by means of a link h². A trip-hook h' is designed to engage said lever h, said hook serving the same purpose as the trip-lever d'. One end of lever h is pivoted at h³ 75 to a bracket or frame h⁴, and to the other end of said lever is connected a weighted rope, as in Fig. 1.

I claim as my invention—

1. The combination, with a wind-wheel, of the hopper having the automatically-moving wing or plate, the tripping mechanism connected thereto, and the rod leading to the wind-wheel, substantially as set forth.

2. The combination, with a wind-wheel, of the hopper having the pivoted wing or plate, the weight connected thereto, the wind-wheel-regulating rod, the lever to which said rod is connected, the trip, and the rope or chain connecting said weight and trip, substantially as set forth.

3. The combination, with a wind-wheel, of the hopper having the pivoted wing or plate, the weight connected thereto, the rope or chain, the trip-lever, the quadrant or lever, the weighted rope or chain connected thereto, and the connecting rod or bar leading to the wind-wheel, all constructed and arranged substantially as set forth.

In testimony whereof I affix my signature in presence of two witnesses.

RILEY HALSEY SARGENT.
